UNITED STATES PATENT OFFICE.

ALEXANDER FORSYTH, OF STANDISH, MICHIGAN.

COMBINED AWNING AND HOUSE CONSTRUCTION.

1,171,510.

Specification of Letters Patent. Patented Feb. 15, 1916.

Application filed March 18, 1915. Serial No. 15,371.

To all whom it may concern:

Be it known that I, ALEXANDER FORSYTH, a citizen of the United States, residing at Standish, in the county of Arenac and State of Michigan, have invented certain new and useful Improvements in Combined Awning and House Construction; and I do hereby declare the following to be a full, clear, and exact description of the invention, such as will enable others skilled in the art to which it appertains to make and use the same.

This invention relates to awnings, and pertains more particularly to awnings adapted for protecting all four sides of buildings, such as small portable houses, invalids' sleeping quarters and buildings of like nature, in which the upper part of the wall is open to the air, but screened against flies and other insects.

In this class of buildings it is desirable to use an awning that will, when raised, protect all four sides of the building from the sun, the awning forming practically a wide-projecting eave clear around the building, and when lowered will form a curtain that lies close to the side walls, closing all the screened openings against wind and rain.

It is a further object of my invention to provide an awning construction of the class described, having means by which the occupant can easily and quickly raise or lower any side or all four sides of the awning without going out of the room, thereby avoiding exposure to the weather.

A still further object is to so construct the awning devices that they will form an integral part of the building, and so arranged that the awning posts comprise also the corner posts of the frame, the posts being so made that they not only act as awning supports and guides, but also enable the side walls of the building to be easily and rapidly assembled or taken down.

With these and certain other objects in view that will appear later in the specification, my invention consists in the devices described and claimed and the equivalents thereof.

In the drawings, Figure 1 is a perspective view, broken away in part, showing a building with my improved awning attached. Fig. 2 is a perspective detail of a corner post and its awning arm. Fig. 3 is a part sectional top plan view of the

parts shown in Fig. 2. Fig. 4 is a plan view of one corner of the frame of the building, showing the manner of connecting the sills to the corner post.

As is clearly shown in the drawings, the device consists in an awning or curtain of canvas, or any suitable material, adapted to be attached at one edge to the roof 2 of the building, and so shaped that it will when raised form substantially a continuation of the roof around all four sides of the building.

The outer edge of the awning 1 is reinforced with a cord or rope 1^a stitched or otherwise secured to it, the rope extending clear around the building. At each corner of the building, and hinged at its upper end to the corner post 3 is an awning arm 4, which in its raised position has practically the same slope as the roof, and when lowered, lies flat against the outer face of the corner post. The post 3 is of triangular cross-section, two of its sides forming abutments against which the side walls 4^a and 5 of the building are secured, and its third side forming the outer face of the corner, the face being preferably at an angle of approximately forty-five degrees with the side walls, and forming a beveled corner of the building. This construction enables the arm 4 to be securely hinged so it will extend diagonally from the corner when raised, and will lie flat against the corner when lowered.

The corner post 3 is provided with a longitudinal slot 6, through which loosely passes a bar 7 pivoted at its upper end 8 to the arm 4, and provided with a pivotally mounted sliding block 9 that travels up and down the outer face of the corner post 3 when raising the arm 4. The inner or lower end of bar 7 projects into the building and serves as a handle by which the arm 4 is manipulated. When the arm is in its raised position, the angle of the bar 7 with relation to the post may be such that the block 9 will be held in place by friction against the face of the post, or a suitable fastening bolt or pin 10 may be provided in the post to keep the arm from dropping.

The operation of the awning is as follows: To raise the curtain, the occupant of the building merely pushes outwardly and upwardly on the bar 7, thus raising the arm 4 and the awning at one corner of the building. After securing the bar by means of pin 10,

he raises and fastens the other three arms. The raising of the fourth arm pulls the cord at the outer edge of the awning taut, thus tightening the entire awning, in a similar manner to the tightening of an umbrella cover when the ribs are raised. In case of storm or wind, one or more sides of the awning can be dropped by releasing the corresponding bars 7, without leaving the room.

10 The triangular corner post not only serves as a convenient means for supporting the awning arm and guiding the bars 7, but also enables the sides of the building to be readily assembled and taken down. The construction by which this object is attained is illustrated in plan in Fig. 4, where 11 and 12 are the sills, which are clamped to the corner post by means of a diagonal brace 13 having its ends mortised into the sides of the sills, and having a bolt 14 passing through it and through the corner post, the bolt being fastened by a nut 15. The ends of the diagonal brace 11 are also bolted to the sills, as at 16. The head of bolt 13 is preferably recessed into the flat face of the corner post 3.

20

25

By the means above described, I have produced an awning construction for buildings of the class described, that is easy to assemble and to operate, and can be quickly adjusted to suit any conditions of weather without making it necessary for the occupant to leave the building.

Having thus described my invention, what I claim and desire to secure by Letters Patent is:

30 1. In a device of the class described, the combination of a building frame, a corner post, an arm hinged at its upper end to said

corner post and adapted to be raised and lowered in the plane of the diagonal of said post, a bar pivoted at its upper end to said arm, the said corner post formed with a diagonally disposed slot to receive said bar, and an awning carried by said arm, for the purposes set forth.

40 2. In a device of the class described, the combination of a building frame, a corner post of triangular cross section having its diagonal face disposed outwardly, an arm hinged at its upper end to the diagonal face of said post, a bar hinged at its upper end to said arm, the said corner post formed with a diagonally disposed slot to receive said bar, a rope secured to the end of said arm, and an awning carried by said arm and rope for the purposes set forth.

45 3. In a device of the class described, the combination of a building frame, a corner post of triangular cross section having its diagonal face disposed outwardly, an arm hinged at its upper end to said corner post, a bar pivoted at its upper end to said arm, said corner post formed with a diagonally disposed slot to receive said arm, a pivotally mounted sliding block secured to said bar, and adapted to engage the outer face of said post, a rope secured to the end of said arm, and an awning carried by said arm and rope for the purposes set forth.

50 55 In testimony whereof, I affix my signature in presence of two witnesses.

ALEXANDER FORSYTH.
